UNITED STATES PATENT OFFICE.

GARROLD L. BAILEY, OF NEWARK, NEW JERSEY.

DESIGN FOR A SOUND AMPLIFIER.

Application filed August 28, 1925. Serial No. 14,622. Term of patent 3½ years.

To all whom it may concern:

Be it known that I, GARROLD L. BAILEY, a citizen of the United States, residing in the city of Newark, in the county of Essex and State of New Jersey, have invented a new, original, and ornamental Design for a Sound Amplifier, of which the following is a specification, references being had to the accompanying drawings, forming a part thereof.

In the drawings, Figure I represents a front view and Figure II represents a side view of a sound amplifier, showing my new design.

I claim:

The ornamental design for a sound amplifier, as shown.

GARROLD L. BAILEY.
